(57) **CLAIM**

The ornamental design for a tablet computer, as shown and described.

DESCRIPTION

FIG. 1 is a front, right side, perspective view of a tablet computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view in a folded configuration thereof;

FIG. 9 is a front view in a folded configuration thereof;

FIG. 10 is a rear view in a folded configuration thereof;

FIG. 11 is a left side view in a folded configuration thereof;

FIG. 12 is a right side view in a folded configuration thereof;

FIG. 13 is a top view in a folded configuration thereof; and,

FIG. 14 is a bottom view in a folded configuration thereof. The broken lines shown in the drawings depict portions of the tablet computer that form no part of the claimed design.

1 Claim, 9 Drawing Sheets
